UNITED STATES PATENT OFFICE

2,648,967

LOCKING DEVICE FOR WINDOW LATCHES

Neil O. Holmsten, New Rochelle, N. Y.

Application December 22, 1949, Serial No. 134,576

6 Claims. (Cl. 70—89)

1

This invention relates to locking devices for rotatable latches of the type used for hinged windows and the like and has for an object to provide a built-in, unitary latch and lock which is compact and dependable and is suited to commercial production methods.

Other objects and advantages will be apparent as the nature of the invention is more fully disclosed.

The novel features which are characteristic of this invention will be better understood from the following description, taken in connection with the accompanying drawing, in which a specific embodiment has been set forth for purposes of illustration.

In the drawing:

Fig. 1 is a front elevation of a latch and lock embodying the invention as applied to a window frame;

Fig. 2 is a horizontal section taken on the line 2—2 of Fig. 1;

Fig. 3 is a horizontal section taken on the line 3—3 of Fig. 1;

Fig. 4 is a rear elevation of the latch;

Fig. 5 is a section taken on the line 5—5 of Fig. 3; and

Fig. 6 is a section taken on the line 6—6 of Fig. 4.

Referring to the drawing more in detail the invention is shown as applied to a latch for a window or the like having a sash 10 closing against a fixed frame 11. The latch comprises a base plate 12 attached to the sash 10 closing against a fixed frame 11. The latch comprises a base plate 12 attached to the sash 10 by suitable means such as non-removable screws 13 and carrying a cylindrical support 14. A hub 15 carrying a latch finger 16 and a handle 17 is journaled on the support 14 for rotation. The latch finger 16 is adapted to engage a keeper 20 which is attached to the fixed frame 11.

A lock barrel 21 is secured in the support 14. The barrel 21 has a key 22 which prevents rotation thereof. A key actuated lock cylinder 23 is journaled to rotate in the barrel 21 and is secured against rotation therein by removal of the key. The lock cylinder and barrel are of standard construction and may be of any type actuated by a key for securing or releasing the cylinder for rotation. The cylinder is eccentrically mounted in the barrel 21 and the barrel 21 is eccentrically positioned in the support 14 in such a manner that the cylinder 23 is centered in the support 14.

The base plate 12 is formed with a recess 24 in

2

its under surface in which a disc 25 is seated. Screws 26, extending through arcuate slots 27 in the base plate 12 secure the disc 25 to the hub 15 for rotation therewith. The slots 27 limit the rotation to about 90° as shown. The screws 26 are formed with shoulders 28 and cylindrical surfaces 29 to provide smooth surfaces sliding in the arcuate slots 27. A rectangular tongue 30 on the end of the cylinder 23 is seated in a slot 31 in the disc 25 to cause the disc and cylinder to rotate as a unit.

In the latch and lock above described a standard lock barrel and the latch hub are concentrically mounted, one on the inside and the other on the outside of a fixed cylindrical support and are joined by a disc which is entirely concealed in the base plate and cannot be removed after the base plate is attached to the sash. The size of the hub is not appreciably greater than that of a standard latch without locking means.

The latch as above described is applicable to various uses such as swinging windows or doors, automobile doors, or the like. The latch finger and handle are illustrative only and may take any of the usual latch forms such for example as a sash latch for sliding windows. Various adaptations will be apparent to a person skilled in the art.

What is claimed is:

1. A locking device comprising a base plate to be attached to a member to be locked, a cylindrical support carried by said base plate and extending outwardly therefrom, a hub carrying a latch member journaled on said cylindrical support for rotation thereon, a lock barrel fixed in said cylindrical support, a key actuated lock cylinder rotatable in said barrel and adapted to be locked thereto against rotation, said base plate having an opening registering with said cylinder and an arcuate slot registering with said hub, a securing member disposed on the under side of said base plate attached to said cylinder to rotate therewith and securing means extending through said slot to secure said member to said hub to cause the cylinder and hub to rotate in unison.

2. A locking device, as set forth in claim 1, in which said cylinder is eccentric with respect to said barrel, but concentric with said hub.

3. A locking device, as set forth in claim 1, in which said securing means comprises a pin attached to said securing member and extending through said slot to secure the same to said hub.

4. In a locking device, as set forth in claim 3, a tongue on the end of said cylinder securing the same to said disk.

5. A locking device, as set forth in claim 1, in which said slot has ends positioned to form stops to limit the rotation of said hub.

6. A locking device comprising a base plate to be attached to a member to be locked, a cylindrical support carried by said base plate and extending outwardly therefrom, a hub carrying a latch member for rotation therewith and being journaled on the outside of said cylindrical support, a key-actuated lock cylinder rotatably mounted inside of said support and adapted to be locked against rotation in said support, an arcuate slot in said support and means extending through said slot for securing said lock cylinder to said hub to prevent rotation of said hub with respect thereto.

NEIL O. HOLMSTEN.
